UNITED STATES PATENT OFFICE

PAUL FELIN FINDEISEN, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

LOUD-SPEAKER

Application filed April 10, 1925, Serial No. 22,018, and in Germany April 25, 1924.

My invention relates to electro-acoustic devices by means of which energy in the form of sound waves emanating from any source of sound is changed into electrical energy, or, 5 conversely, electrical energy in the form of the corresponding sound variations is changed into energy in the form of sound waves.

An object of the invention is to provide a device of this character that will be free from 10 distortion to the greatest possible extent.

Other objects will be apparent from the following description and claims when considered with the accompanying drawing in which:

15 Fig. 1 is a diagrammatic illustration of one embodiment of my invention.

Fig. 2 is a diagrammatic illustration of another modification.

20 Fig. 3 is a diagrammatic illustration of a combination of the first two modifications.

Fig. 4 is a cross section on the line 4—4 of either Fig. 2 or Fig. 3, showing also the individual sound horns leading to a single common horn.

25 It is a well-known fact that in loud-speakers in which acoustic vibrations are produced by virtue of the vibration of a membrane or diaphragm, marked distortion of the sound vibrations are caused due to the natural frequency of the diaphragm. In order that sound transmission free from distortion may be obtained, it is necessary to use, either diaphragm whose natural frequency does not fall 30 inside the range of sounds or tones, or else elements must be chosen for the transmission of sound possessing a great number of natural frequencies so that corresponding resonance frequencies are obtained for the sounds to be transmitted.

40 Now, the present invention has recourse to the latter arrangement. It has been discovered that a satisfactory rendition of sound is made possible if, instead of a diaphragm, steel chords are used which are set into vibration by the telephone magnet. Now, in order that as pure a timbre as possible may be produced for different tones, it is necessary that a great 45 number of chords be exposed to the influence 50 of the current variations caused by the sounds.

This can be done in various ways as explained in the following description.

For instance, it is possible to influence several chords by the fields of a single telephone magnet, in a way as diagrammatically 55 illustrated in Fig. 1, in which m, m , are the pole shoes of an electro-magnet over which seven chords "O" of varying length are stretched, as indicated in the drawing. The chords are fastened on a ring r . For tuning, if desired, screws D can be used by means of which re-adjustment in tension is possible. Taken together, the tensioned chords act just 60 like a diaphragm possessing a plurality of natural frequencies.

65 Another plan of carrying the idea into practice would be to furnish each telephone magnet with just one chord, and to use at the same time a plurality, or a great number, of such magnets in the case of which each chord 70 possesses its own natural period. This arrangement is shown in Figs. 2 and 4. A base plate P has a number of openings therein into which fit the actuating elements 1 to 7 inclusive each having an electromagnet M therein. At the center of the base plate P is an annular ridge T . Arranged across the field of influence of each magnet M is a steel chord 75 extending from the annular ridge T . The chords extend to, and their tension is adjusted by, adjusting devices D of any convenient kind arranged near the periphery of plate P .

80 Each element 1 to 7 inclusive has a cap R thereover, (see Fig. 4) said caps each supporting a small horn H . The outer ends of horns H open into plate K which forms part of a large common horn L . This is a very favorable arrangement, the sound vibration from each of the small horns being supplied 85 to the single large horn.

85 The individual magnets M are connected in parallel.

90 The number of individual sound transmitters to be used, as a general rule, may probably have to be chosen different according to the sounds to be transmitted. For transmission of music, faithful transmission or reproduction is realizable by having the steel 95 chords correspond to the seven fundamental 100

sounds of the scale. The letters *a*, *b*, *c*, *d*, *e*, *f* and *g*, indicated with the chords in Fig. 2 correspond to the seven fundamental tones.

It goes without saying that for the object of changing the pitch of the chords, bridge pieces can be used, or else other well-known means for the same object. In the case of transmission of music made, for instance, by wind (brass) instruments, the distortion of the tones due to natural frequencies of a diaphragm becomes by far less noticeable than for string instruments or piano music. Hence, arrangements may also be so chosen that a telephone magnet is provided with a good diaphragm which may preferably be disposed so as to be disconnected when desired, so that it can be used only when required.

Now referring to Figs. 3 and 4, wherein is shown a combination of the first two embodiments, actuating element 6 is shown provided with seven chords which may have their natural periods arranged according to the seven fundamental tones in the manner of the modification shown by the described in connection with Fig. 1.

Furthermore, any one of the other actuating elements may have one or more chords which chords may be arranged so that their natural periods have any desired values.

Having described several embodiments of my invention, I am entitled to all modifications thereof as fall fairly within the spirit and scope of the following claims:

1. An electro-acoustic device comprising electro-magnetic means having a core which in cross section has parallel sides, and seven chords of magnetic material stretched transversely of the end of said core, each of said chords being tuned to a different one of the seven fundamental tones in an octave of the musical scale.

2. Means for the intertransposition of sound and electrical energy comprising a sound chamber and a plurality of electro-acoustic devices cooperating therewith, each of said devices comprising electro-magnetic means including a core which in cross section has parallel sides, and one or more chords of magnetic material stretched transversely of the end of the core and tuned to vibrate only at a predetermined frequency.

3. A sound reproducer comprising a plurality of vibratory elements each of which is suspended to vibrate at a predetermined natural period different from the natural periods of the other vibratory elements, means for vibrating said elements at their natural periods, a separate sound collecting and amplifying horn for each of said elements, and a single horn for collecting and amplifying the sound waves from said separate horns.
